UNITED STATES PATENT OFFICE.

NOËL EVELYN DUFFY, OF LONDON, ENGLAND.

GUIDE FOR VALVES OF INTERNAL-COMBUSTION ENGINES.

Application filed December 15, 1925, Serial No. 75,640, and in Great Britain January 9, 1925.

This invention relates to improvements in guides for valves for use with internal combustion engines.

The object of the invention is to provide means for mounting a valve in such a manner as to avoid the failure of the valve to seat properly. In internal combustion engines it commonly happens that the valve head fails to seat itself properly on the seating in the cylinder body, when the engine has run for a short time, owing to the fact that the valve seating becomes displaced by reason of the head of the engine becoming much hotter than the part of the engine which carries the valve guide. This results in the valve seating becoming displaced laterally with regard to the valve, with a consequent leakage and loss in pressure within the cylinder.

With a view to avoiding this objection the valve guide has in some cases been mounted so as to be capable of rocking with regard to the engine casing but this attempted solution of the difficulty is unsatisfactory inasmuch as it leads to the valve occupying a position which is not co-axial with the seating.

According to the present invention guiding or packing means are provided for the valves of internal combustion engines which permit of the lateral displacement of the valve substantially parallel to itself. When the valve seating becomes displaced relatively to the portion of the engine which carries the valve guide, the valve is able to alter its position but still to remain co-axial with the valve seating. One or more, preferably a number, of guiding elements closely surround the valve stem, and are carried by a holding or containing member mounted at a convenient point on the engine casing, these guiding elements being capable of lateral movement within the containing member and the ends of the containing member, through which the valve stem passes being apertured to permit of a sideways displacement of the valve stem relative to the containing member. Preferably these guiding elements alternate with other, spacing, elements which fit closely within the containing member, but while surrounding the valve stem are spaced therefrom. The guiding and spacing elements thus form a labyrinth packing resembling the packing sometimes used for the connecting rods of pistons and slide valves in steam engines, but at the same

time the guiding members and the containing member permit of a lateral movement of the valve stem. The guiding and spacing elements may be of a suitable metal, or the elements which closely surround the valve stem may be of carbon, or of metal with a carbon bushing. The carbon used for the guiding and spacing elements may be a manufactured graphite product such as is used to-day for the carbon packing-gland rings of steam turbines and for the carbon brushes of electric generators and motors. A pure graphite composition is specially suitable on account of its capacity to withstand a high temperature and of its low coefficient of friction. In some cases the carbon may contain an admixture of copper or other metal to increase the heat conductivity of the carbon element. The guiding and spacing elements are preferably pressed into close engagement with one another by means of a spring.

The invention is illustrated in the accompanying drawing in sectional elevation as applied to the intake valve of an internal combustion engine.

The valve A rests on the valve seating B in the cylinder wall and the valve stem C passes down through the guiding means and carries the usual collar D, between which and the flange E of the guide container or holder F is the usual spring G for holding the valve on its seat.

The valve guide is made up of a number of guiding elements H, H and spacing elements J, J. The elements H, H are rings of carbon which are a sliding fit on the spindle C but are slightly less in cross sectional area than the interior of the member F mounted or formed on or at a convenient point on the engine casting, and containing or holding the guide elements, so that there are spaces K surrounding these elements H. The rings H may also be of a suitable metal. The spacing elements J, which alternate with the elements H, are rings of suitable metal and are a snug fit in the containing member F, but internally are of larger diameter than the spindle C, so that spaces L are left between the spindle and the rings J. The elements H and J are pressed upwards and into close contact with one another by a light spring M, resting on the spindle collar D and bearing against the lowest element J'.

The element J' thus closes the bottom end

of the guide containing member F, and the upper end of the member F is closed by the inturned flange F', which does not fit closely round the valve stem C, but is spaced therefrom.

If the valve seating B is displaced laterally with regard to the guide containing member F, owing to the cylinder head heating more than the portion of the engine in 10 which the member F is carried, the spindle C, with the guide elements H can move slightly laterally, the spindle remaining parallel to itself, and so the valve A can locate itself accurately and concentrically in the 15 seating B, the rings H sliding laterally over the spacing rings J.

It will be seen that the guiding and spacing elements described form a labyrinth packing for the valve stem, with all the advantages that this form of packing is known to offer.

It is not necessary that a separate spring M should be provided to act on the guiding and spacing elements, though this is the 25 preferable arrangement. The element J' might be formed with a flange to take the thrust of the spring G, which would then serve a double purpose.

I claim:—

30 1. Guiding means for valves of internal combustion engines comprising a container surrounding and spaced from the valve stem, an inturned flange at one end of said container the inner periphery of said flange 35 being spaced from the valve stem, a guiding element fitting closely around the valve stem within the container said guiding element being capable of lateral movement within the container and means for maintaining the guiding element in close contact with the flange of the container.

2. Guiding means for valves of internal combustion engines comprising a container surrounding but spaced from the valve stem, 45 a guiding element fitting closely around the valve stem within the container, said guiding element being capable of lateral movement within the container and a further element surrounding but spaced from the valve 50 stem and in close contact with the guiding element and fitting closely against the interior surface of the container.

3. Guiding means for valves of internal combustion engines comprising a container 55 surrounding but spaced from the valve stem a plurality of guiding elements fitting closely around the valve stem within the container, said guiding elements being capable of lateral movement within the container, and spacing elements between the 60 guiding elements said spacing elements surrounding but being spaced from the valve stem and being in close contact with the guiding elements and the interior surface of 65 the container.

4. Guiding means for valves of internal combustion engines comprising a container surrounding but spaced from the valve stem, a plurality of guiding elements closely fitting around the valve stem within the container, 70 said guiding elements being capable of lateral movement within the container and spacing elements alternating with the guiding elements, said spacing elements surrounding but being spaced from the valve 75 stem and being in close contact with the guiding elements and the interior surface of the container.

5. Guiding means for valves of internal combustion engines comprising a container, 80 surrounding but spaced from the valve stem, guiding elements of carbon adapted to fit closely round the valve stem within said container, said guiding elements being capable of lateral movement within the container 85 and spacing elements between the guiding elements.

6. Guiding means for valves of internal combustion engines comprising a container surrounding but spaced from the valve stem, 90 guiding elements adapted to fit closely round the valve stem within said container, said guiding elements being capable of lateral movement within the container, and spacing 95 elements of metal between the guiding elements.

7. Guiding means for valves of internal combustion engines comprising a container surrounding and spaced from the valve stem, 100 an inturned flange at one end of said container the inner periphery of said flange being spaced from the valve stem, a guiding element fitting closely around the valve stem within the container, said guiding element 105 being capable of lateral movement within the container and a spring adapted to urge the guiding element into close contact with the flange of the container.

8. Guiding means for valves of internal combustion engines comprising a container 110 surrounding but spaced from the valve stem, a guiding element fitting closely around the valve stem within the container, said guiding element being capable of lateral movement within the container, a further element surrounding and spaced from the valve stem, and in close contact with the guiding element and fitting closely against the interior 115 surface of the container and means for maintaining the elements in close contact with one another.

9. Guiding means for valves of internal combustion engines comprising a container surrounding but spaced from the valve stem, 120 a plurality of guiding elements fitting closely around the valve stem within the container, said guiding elements being capable of lateral movement within the container, spacing elements between the guiding elements, said spacing elements surrounding but being 125

spaced from the valve stem and being in close contact with the guiding elements and the interior surface of the container, and means for maintaining the guiding and spacing elements in close contact with one another.

10. Guiding means for valves of internal combustion engines comprising a container, surrounding but spaced from the valve stem, a labyrinth packing around the valve stem within the container, said labyrinth packing

being adapted to permit movement of the valve parallel to itself, a fixed collar on the valve stem and a spiral compression spring arranged between said fixed collar and the 15 lowest member of the labyrinth packing and adapted to maintain the parts of the labyrinth packing in position.

In testimony whereof I have signed my name to this specification.

NOËL EVELYN DUFY.
